F. GOMPF.
PLANT PROTECTOR.
APPLICATION FILED APR. 30, 1914.

Patented Apr. 6, 1915.

UNITED STATES PATENT OFFICE.

FRANK GOMPF, OF CLEVELAND, OHIO.

PLANT-PROTECTOR.

1,134,841.

Specification of Letters Patent. Patented Apr. 6, 1915.

Application filed April 30, 1914. Serial No. 835,475.

To all whom it may concern:

Be it known that I, FRANK GOMPF, a citizen of the United States, residing at Cleveland, in the county of Cuyahoga and State 5 of Ohio, have invented certain new and useful Improvements in Plant-Protectors; and I do declare the following to be a full, clear, and exact description of the invention, such as will enable others skilled in the art to 10 which it appertains to make and use the same.

My invention relates to improvements in plant protectors and has for its primary object to provide a simple device of this character 15 which may be inexpensively constructed and yet one which will effectually guard the plant, to which it is applied, against frost and rough usage in handling.

In carrying out the above end, I provide a 20 flexible sleeve slit throughout its length and having a number of fasteners on its meeting edges, an expansible slit skirt at the lower end of said sleeve, means whereby said skirt may be contracted, a tab on the upper end 25 of the sleeve, and coacting fasteners carried by said tab and sleeve.

A secondary object of the invention is to construct the skirt in such a manner as to allow the same to be expansibly or adjustably secured to flower pots and tubs of different sizes.

A still further object of the invention is to construct the entire device in the most simple manner consistent with its proper operation.

With these objects in view, the invention resides in certain novel features of construction and combination, herein described and claimed and shown in the drawings, wherein:

Figure 1 is a perspective view showing the application of my invention; Fig. 2 is a detail vertical section, taken upon the line 2-2 of Fig. 1; Fig. 3 is a horizontal section taken upon the line 3-3 thereof; and Fig. 4 40 is a plan view of the protector removed from the plant, showing more particularly its construction.

In the accompanying drawings, I have shown my invention as including an upright sleeve 1 which is slit throughout its length 50 and provided on its meeting edges with a plurality of coacting fasteners 2 and 3, said

fasteners being here shown of the type usually employed for the purpose of fastening gloves and the like.

Depending from the lower end of the sleeve 1 and formed of flexible material, is a skirt 4 which is slit throughout its length, said skirt being plaited, as indicated at 5, and being of greater diameter at its lower 60 end than at its upper end, said lower end being turned upon itself and stitched to provide a guide 6 for a draw string 7, the latter being adapted to have its free ends tied when the meeting edges of the skirt are brought 65 together around a flower pot or tub, indicated at P in the drawings.

When the device is in position upon a plant, the fasteners 2 and 3 are secured and the draw string 7 is tied, as above suggested. 70 It now becomes expedient to provide a simple and efficient means for closing the upper end of the sleeve, said means being here shown in the form of a flexible tab 8 which is attached to the upper end of the sleeve 75 and which carries a fastener 9 for coaction with a complementary fastener 10, carried by the sleeve.

The sleeve 1 is preferably formed of inner and outer layers 1' and 1'', between 80 which a lining of felt or other suitable insulating material is positioned, the three layers being preferably secured together by longitudinal rows of stitching.

From the foregoing description and the 85 accompanying illustration, the construction and manner of application of the invention will be readily understood. It may be well, however, to set forth the manner in which my improved protector is applied to plants 90 having the general characteristics of ferns or palms. In thus applying the invention, the uppermost end of the sleeve 1 is fastened around the shank or trunk of the plant and gradually pulled upwardly, this upward movement drawing the leaves of the plant inwardly, after which the remaining fasteners are secured for the purpose of retaining said leaves. When the entire sleeve is 95 correctly positioned, the tab 8 is fastened and the skirt 5 is secured around the pot or tub, as before suggested.

The protectors may be made in various sizes for adaptation to plants of different

heights and various forms of material may be employed for carrying out the objects of the invention.

Having thus described my invention, what 5 I claim as new and desire to secure by Letters Patent is:

1. A plant protector of the character described, comprising a cylindrical member split longitudinally throughout its length, a 10 plurality of coöperating fasteners relatively arranged upon the meeting edges of said member, a flexible skirt depending from the lower edge of the latter, said skirt having a tapered formation from its attached to its 15 free end whereby when the latter is positioned upon the upper edge of a flower pot so as to circumscribe the same, said cylindrical member rising therefrom will be supported in a vertical position thereby, a draw 20 string around the lower edge of said skirt for contracting the same, and a closer for the upper end of said cylindrical member substantially as and for the purpose set forth.
- 25 2. A plant protector of the character described comprising a cylindrical member, the

latter being split longitudinally throughout its length and including two layers of flexible material with an insulator intermediate the same, a plurality of coöperating fasteners 30 relatively arranged upon the meeting edges of said member, a flexible skirt depending from the lower edge of the latter, said skirt having a tapered formation from its attached to its free end whereby when the latter is positioned upon the upper edge of a flower pot so as to circumscribe the same, said cylindrical member rising therefrom will be supported in a vertical position 35 thereby, a draw string around the lower edge of said skirt for contracting the same, and a closer for the upper end of said cylindrical member substantially as and for purpose set forth.

In testimony whereof I have hereunto set 40 my hand in presence of two subscribing witnesses.

FRANK GOMPF.
